UNITED STATES PATENT OFFICE.

JOHN M. SINER, OF NEW YORK, N. Y., ASSIGNOR TO VENUS MANUFACTURING CO., OF NEW YORK, N. Y., A CORPORATION OF NEW YORK.

CLASP FOR GARMENT-SUPPORTERS.

No. 890,382.

Specification of Letters Patent.

Patented June 9, 1908.

Application filed May 25, 1907. Serial No. 375,674.

To all whom it may concern:

Be it known that I, JOHN M. SINER, a citizen of the United States of America, residing at New York, in the county of New York and State of New York, have invented new and useful Improvements in Clasps for Garment-Supporters, of which the following is a specification.

This invention relates to improvements in 10 clasps for garters and other garment supporters of that general type comprising a pair of coöoperating spring jaws, and an engaging lever or member connected with one jaw and designed for engagement with the 15 other jaw, the engagement between said member and jaw serving to maintain the member in engaging position.

The object of the present invention is to 20 provide a construction by which the engaging lever or member is adapted to be more readily gripped for adjustment to released position.

The invention consists of the features of 25 construction, combination and arrangement 25 of parts, hereinafter fully described and claimed, reference being had to the accompanying drawing, in which:—

Figure 1 is a front elevation showing the 30 construction of the device as adapted for use upon a garter. Fig. 2 is a similar view of the 35 clasp, showing the lever swung to release position. Fig. 3 is an edge view of the clasp with the lever in locking position. Fig. 4 is a view similar to Fig. 3, with the lever in the 40 position shown in Fig. 2. Fig. 5 is a front elevation of the device as adapted for use as a garment supporter for connecting a lady's shirtwaist and skirt to prevent relative displacement thereof. Fig. 6 is an edge view of the same.

Referring to the drawing, 1 designates a 45 garter composed of elastic material and provided at its ends with engaging members or heads 2 and 3, of which the member 2 has an outwardly opening radial slot 4 communicating with a central circular opening 5 to receive the shank 6 of a headed pin or stud 7, by means of which the clasp or engaging device 8 is pivotally connected with the head 3. 50 When the garter is applied the shank 6 is entered through the slot 4 into the opening 5 for buckling the garter in position, and the engaging device 8 depends vertically therefrom, as illustrated in Fig. 1.

55 The clasp or engaging device 8 comprises a

supporting plate 9 recessed at its opposite edges to produce projecting tongues 10 for engagement with the upper portion of a spring member 11 formed from a single length of spring wire bent to provide a primary spring jaw 12 and a secondary spring jaw 13, said jaws being of approximately equal length, the jaw 12, however, being of greater width than the jaw 13 to permit the free end of the latter to swing therethrough 60 for a purpose hereinafter described. The jaw 12, which is of substantially U-shape, comprises parallel side arms or portions 14 and an end portion 14^a, while the jaw 13, which is generally of U-form, comprises side 65 arms or portions 15 and an end portion 15^a, the tongues 10 being folded around the upper ends of the side arms of the jaw 12 to connect the spring member 11 at or adjacent the point of juncture of the two jaws to the plate 70 9, the joining portions of the wire of said member being seated within the said recesses in the supporting plate.

An operating member or lever 16, formed from a single length of material, has an engaging portion or end 17, an offset portion or shoulder 18 projecting from the relatively inner end of the engaging portion, and a handle portion 19 projecting from the relatively outer end of the offset portion. The engaging portion 17 of the lever is preferably formed 80 of double thickness, by bending the material, as shown, the relatively lower leaf or portion of this double formation being extended in rear of the offset portion 18 and rolled, as at 85 20, to receive the end bar 15^a of the jaw 13, to pivotally support said lever upon said jaw.

In practice assuming the parts to be in the 90 position illustrated in Figs. 2 and 4, the jaw 13 will stand in spaced relation to and in advance of the jaw 12, while the lever 16 will hang downward with its engaging portion 17 projecting upward and at a slight rearward inclination between the jaws. With the parts in this position, the edge of the hose or 100 other garment is entered between the jaw 12 and the engaging portion 17 of the lever 16, which latter is thereafter swung upwardly to the position shown in Figs. 1 and 3, whereupon the portion 17 will ride upon and engage 105 in rear of the bar 14^a, thus clamping the garment securely between the latter and the lever. In this operation the portion 17 of the lever acts in the nature of a cam to contract and bow the jaw 13 and pull the free end of 110

said jaw through the jaw 12, whereby the cross bar 14^a of the jaw 12 will rest directly against the offset portion or shoulder 18 of the lever, while the cross bar 15^a of the jaw 13 will be disposed beyond the said end 14^a of the jaw 12. This position of the parts, which is primarily due to the approximately equal length of the jaws and the specific construction of the engaging lever and its mode 10 of connection with the jaw 13, whereby the secondary jaw is bowed to pass through the primary jaw, insures a spring tension on said lever from the end bar 14^a of the jaw 12, and, as a result of this tension and the fact that 15 the end bar 14^a bears against the offset portion 18, such tension is directly exerted toward maintaining the lever in clamping or engaging position, establishing a self-locking action of said lever without the use of 20 auxiliary locking means.

It will be observed that the arms 15 of the jaw 13 are convergently bent toward the stationary or fulcrum end of said jaw, as indicated at 15^b, so that the latter-named portion 25 will lie beneath lever 16 when the latter is in engaging position, whereby the jaw 13 is caused to act as a support to hold the free end of the lever spaced from the plate 9. In addition the upper or fulcrum ends of the 30 arms are converged or curved toward the plate 9, while the free end of the lever is bent or curved slightly outward to produce, when the lever is in engaging position, a recess 21 for the insertion of the nail of the forefinger 35 to permit the latter to be inserted into the space between the plate 9 and the free end of the lever 16, by which the latter may be readily gripped between the forefinger and thumb and swung to release position, thus disconnecting the clasp from the garment.

In Figs. 5 and 6 I have shown the application of the same principle to a garment support designed for connecting a lady's shirtwaist and skirt to maintain the same in 45 proper relative position. The said support comprises a spring member 11^a consisting of a single piece of wire bent to provide substantially U-shaped jaws 12^a and 13^a. The supporting plate 9 is here dispensed with; 50 but the construction is otherwise the same as that disclosed in the garment clasp before described with reference to Figs. 1, 2, 3 and 4, with the exceptions hereinafter noted. The

engaging member or lever 16^a here has the same self-locking function, and the lower 55 end of the shirtwaist is designed to be clamped between the jaws 12^a and 13^a, while the handle end of the lever is centrally slotted and the freed portion of the metal bent to provide a hook 22 to engage a loop or eye 60 on the waist band of the skirt. The clamp will thus connect the upper portion of the skirt with the lower portion of the shirtwaist, preventing the skirt from sagging down and the shirtwaist from being drawn upward 65 and becoming displaced. It will be observed that in this construction also the converging portions 15^c of the arms of the jaw 13^a are arranged to underlie the handle end 70 of the lever when the latter is in engaging position, thus supporting the same so that the forefinger may be slipped between said arms and beneath the lever, allowing the latter to be conveniently grasped and swung to release or non-engaging position.

I make no claim in the present application to the broad features of construction whereby a self-locking action of the lever is attained, as such features are described and claimed in my prior application filed December 11, 1906, Serial No. 347,327, the present invention being restricted to the means for supporting the closed lever and providing a nail or finger space to permit the lever to be readily grasped for an opening movement.

Having thus described the invention, what is claimed as new, is:—

A garment clasp comprising primary and secondary spring jaws, and a lever pivoted to the secondary jaw and adapted to interlock with the primary jaw to hold said jaws closed, said lever being adapted to fold in closed position over upon the secondary jaw, the free end of the lever and the said secondary jaw being relatively formed to limit the 95 closing movement of said lever and provide an intervening nail or finger space for the free engagement of the thumb or finger with said lever and its movement to a jaw-opening position.

In testimony whereof, I affix my signature in presence of two witnesses.

JOHN M. SINER.
